Inventor:
A. Cromfoot

UNITED STATES PATENT OFFICE.

ABEL CROWFOOT, OF CHICAGO, ILLINOIS.

RATCHET TUBE-CUTTER.

Specification forming part of Letters Patent No. 40,023, dated September 22, 1863; antedated March 11, 1862.

To all whom it may concern:

Be it known that I, ABEL CROWFOOT, of Chicago city, in the county of Cook and State of Illinois, have invented a new and useful Machine for the Purpose of Cutting out Tubes from Steam-Boilers; and I do hereby declare that the following is a clear and exact description of the construction and operation of the same, reference being had to the annexed drawings, making a part of this specification, in which—

Figure 1 is a perspective view. Fig. 2 is a longitudinal section. Fig. 3 is a transverse section. Fig. 4 is the cutting portion of the machine. Figs. 5 and 6 is that part of the machine which is used to govern or regulate the position of the cutting instrument.

A is an adjustable screw, the center of which rests against the fire-box or other support to hold the machine steady as a point of motion.

B is an extension-rod running into a cylinder in the body G, (shown by Fig. 2 and the dotted lines of Fig 1,) and is kept in any position by means of set screws and collars C D and E F, thus giving with the threaded end in A the required length, according to the space of the fire-box or other support, with much more facility than by the slow process of the screw alone, common to the ordinary ratchet-drill.

I and H are a collar and a set-screw to fasten the lever of the ratchet J.

M is the ratchet.

L is the spring of K, the dog, and N and O the bolt and nut to hold the dog and spring to the lever of the ratchet.

G is the main body of the machine.

Y is a cylindrical portion of the head Q, inserted into the body G and fastened by a pin P.

Q is the head of the machine, around which passes a collar, R, which collar is kept in its place by a set-screw, S, Fig. 1, and through which collar passes a feed-screw, T, bearing upon a lever, W, placed in a key-bed, which

bed is shown by the dotted lines in the head Q, Fig. 2. Said lever has a dovetailed mortise in its outer end to receive one end of U, the cutting-instrument.

U, the cutting instrument, plays in a mortise in the head Q, and is moved by the set-screw T, pressing upon the lever W, and thus giving the cutting-edge X the proper projection for working.

V is a part of the head Q cut out for the escape of the chips.

The head Q is jointed with the body G in order to be replaced by other heads to suit the size of different tubes.

The operation of my machine is as follows: Set the collars R at such a distance from the cutting-instrument X as may be necessary in order to cut off the tube in the proper place; place the cutter X and head up to the collar R into the tube, then adjust the length of the machine by the extension-rod B so that the center A shall rest upon the fire-box or other support, fastening the extension rod by the set-screws F and D, and placing the collar C against the body G. Having made a center punch-mark upon the front side of the fire-box on a line with the tube to be cut, place the center in it with exactness to steady the machine by turning the center A upon the screw end of the extension rod B. Now, by working the ratchet by means of the handle J, giving the requisite projection of the cutting-edge X by turning the set screw T, the tube is cut off.

What I claim as my invention, and desire to secure by Letters Patent, is—

The combination, with a common ratchet-drill stock, of the cutter U, with either a square or angular-shaped cutting-edge, the lever W, feed-screw T, head Q, and extension-rod B, for the purpose of cutting off boiler-flues in the manner set forth.

ABEL CROWFOOT.
